(57) CLAIM

The ornamental design for a container, as shown.

DESCRIPTION

The purpose of the banana shaped container is to be a retail package that is sold along with the product that it contains. After the customer has removed the contents of the banana shaped container, it can be reused by the customer in many ways.

FIG. 1 is a top, front perspective view of a banana shaped container showing my new design;

FIG. 2 is a top plan view thereof;

FIG. 3 is a bottom plan thereof; and,

FIG. 4 is a top, back perspective view thereof.
